His Attorney*

UNITED STATES PATENT OFFICE.

BERT C. WILLIAMS, OF OCEAN PARK, CALIFORNIA.

SAVINGS BANK.

Application filed October 31, 1921. Serial No. 511,554.

To all whom it may concern:

Be it known that I, BERT C. WILLIAMS, a citizen of the United States, and a resident of the city of Ocean Park, county of Los Angeles, and State of California, have invented certain new and useful Improvements in Savings Banks, of which the following is a specification.

My invention relates to improvements in savings banks and has for its principal object the provision of an improved construction of this character which will be highly efficient in use.

A further object of my invention is the provision of a bank of this character whereby it will be impossible to extract coin from the bank once it is deposited therein.

A further object of my invention is the provision of a construction of a closure member or cover which is hingedly connected to the main body of the bank without the employment of a pintle which is commonly employed in the construction of most banks of this character.

25 A further object of my invention is the provision of a coin controlling means whereby paper money as well as coin, may be deposited into the bank without rolling the same in order to deposit it therein.

30 Other objects will appear hereinafter.

The invention consists in the combinations and arrangements of parts hereinafter described and claimed.

The invention will be best understood by reference to the accompanying drawings forming a part of this specification, and in which,

Fig. 1 is a side elevational view of a bank embodying the invention,

40 Fig. 2 is an edge view of the same, partly in section, to more fully illustrate the coin controlling means,

Fig. 3 is a sectional detail view of the same taken substantially on line 3-3 of Fig. 1,

45 Fig. 4 is a sectional detail view of the same taken substantially on line 4-4 of Fig. 1,

Fig. 5 is an elevational view of the key controlling the cover locking means embodied in the invention;

50 Fig. 6 is a sectional detail view taken substantially on line 6-6 but showing the bank bottom side up to more fully illustrate the coin controlling means embodied in the invention.

The preferred form of construction as illustrated in the drawings, comprises a metallic coin compartment or body 10, open at one side, the end walls and one of the side 60 edge walls of the housing being set back an appropriate distance from the adjacent edges of the sides of the housing and the other of the side edge walls of the housing is semicircular in form, so that when the 65 body is properly formed, it will have the appearance of a book. The preferred form as illustrated in the drawing represents a book bank, however, the form or shape of the body may take the appearance of other 70 forms. A closure member or cover 11 is hingedly mounted to the body and constitutes one side of the body and is formed from a rectangular sheet of material. One of the side edges 12 of the cover is bent 75 downwardly and then back upon itself to form a recess 13 which extends longitudinally with respect to the cover. The upper end 14 of the semicircular shaped side edge of the body is bent downwardly forming a 80 depending flange 15 adapted to engage the recess 13 to hingedly connect the cover to the body 10 in such a manner as to permit the cover to be readily detached when desired. This construction is such that in 85 hingedly mounting the cover 11, the employment of a pintle is obviated and by obviating the pintle, it is impossible to remove the cover 11 until released by the locking mechanism which I will now proceed to explain.

The locking mechanism embodied in my invention comprises a rectangular shaped partition member 16 which extends longitudinally with respect to the side edge of the body, opposite the semicircular formed edge and is mounted within the body, in spaced relation with respect to the adjacent side edge. Formed centrally in the partition member 16 is a rectangular shaped transversely arranged recess 17 in which a laterally extending bearing pin 18 is mounted and upon which, within the recess, is a rotatable flanged disc 19. Formed integrally with the flanged edge 20 of the disk 19, on opposite sides thereof, are laterally extending ears 21 each of which bear at their outer ends a laterally extending pin 22 adapted to engage transversely extending slots 23 formed adjacent the inner ends of a pair of oppositely disposed lock plates 24 and 25 which are slidably mounted in the space 26

between the side edge of the body and the partition member 16, and which are adapted to be reciprocated toward and away from each other in the manner which will be hereafter explained. The lateral movement of each of the lock plates 24 and 25 is governed by pins 27 mounted transversely in the space 26 and which engage elongated slots 28 formed in each of the lock plates 24 and 25. The upper edge of each of the lock plates is provided with a notched recess 29 arranged for the reception of a co-operating latch member 30, formed on the back of the cover 11 and which, when engaging the corresponding recess, retains the cover, through the medium of the lock plates, in a locked position on the body of the bank. Mounted in the space 26 adjacent each end of the lock plates 24 and 25, by means of a transversely positioned pin 31, is a leaf spring or clock spring 32, attached to the ends of the lock plates, in any suitable manner, adapted to draw the lock plates away from each other and to normally retain the said lock plates in spaced relation with respect to each other. To unlock the cover 11, a key 34, such as is shown in Fig. 5, having a socket 35 formed in one end of the stem 36, is inserted through the key opening 37. Formed on the end of the stem 36 is a laterally extending arm 38 having a laterally extending pin 39 adapted to engage an aperture 40, formed in the disc 19, when the key is inserted through the key opening 37. By turning the key 34 to the right, the lock plates 24 and 25 are caused to move toward each other releasing the latch members 30 from the notched recesses 29, whereupon the cover can be opened. After the cover is opened the clock or leaf springs 32 and 33 automatically draw the lock plates away from each other. By this arrangement it will be observed that without the proper formed key the cover of the box cannot be removed or opened.

Having described and explained the construction and manner by which the cover of the bank is locked and mounted, I will now proceed to describe and explain the means for controlling the passage of coin through the deposit slot 41, formed centrally in one of the end walls of the body of the bank and extending longitudinally with respect thereto. This means comprises a metallic box-like structure 42 open at the bottom and top thereof and which is fixedly secured to the underside of the end wall and surrounds the deposit slot 41. Positioned within the box-like structure 42, adjacent the top thereof, are two oppositely disposed supporting rods 43 and 44 which extend longitudinally with respect to the side walls of the box-like structure. Mounted eccentrically on each of the supporting rods are a number of rectangular shaped tumblers 45, said mounting being in the manner shown in Fig. 6 of the

drawing. The tumblers 45 are so mounted on the supporting rods 43 and 44 that when the bank is held right-side up the opposite rows of tumblers will fall, by force of gravity, away from each other, and when the bank is held bottom-side up, the opposite rows of tumblers will fall, by force of gravity, towards each other or in the same direction with respect to each other. It is thus seen that once a coin is deposited in the bank it is impossible to extract the same therefrom. As best shown in Fig. 6, of the drawing, when the bank is turned bottom-side up, or in any other similar position, the side walls of the box-like structure or housing 42 limits the pivotal movement of the tumblers 45 in opposite directions with respect to each other.

By operating upon the coin controlling means of savings banks of this character which are now in use, with a knife blade or the like, the coin controlling means can be held in such a position that by shaking the banks the coin will drop out. By my improved coin controlling means this cannot be done, for the reasons that the tumblers fall toward each other, and even if a thin knife blade or the like be passed between the rows of tumblers, the same would engage the sides of the knife blade preventing the coin from dropping out of the bank. Another advantage of my improved coin controlling means is, that bills can be deposited through the coin depositing slots without rolling the same up, thus avoiding unnecessary labor when the money is removed from the bank to be deposited in a commercial bank.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A bank including a coin chamber, a coin slot, a housing having an open bottom surrounding said slot, and tumblers arranged within said housing on opposite sides of said slot, the pivotal movement of said tumblers in opposite directions with respect to each other being limited by the side walls of said housing.

2. A bank including a coin chamber, a coin slot, a housing having an open bottom surrounding said slot, and eccentrically mounted tumblers arranged in said housing on opposite sides of said coin slot, the pivotal movement of said tumblers in opposite direction

with respect to each other being limited by the side walls of said housing.

3. A bank, including a bank body having an opening therein, a closure member for said opening, a coin slot, a housing having an open bottom surrounding said slot, and tumblers arranged within said housing on opposite sides of said slot, the pivotal movement of said tumblers in opposite directions 10 with respect to each other being limited by the side walls of said housing.

4. A bank, including a bank body having an opening therein, a closure member for said opening, a coin slot, a housing having an open bottom surrounding said slot, and eccentrically mounted tumblers arranged in said housing on opposite sides of said coin slot, the pivotal movement of said tumblers in opposite direction with respect to each 20 other being limited by the side walls of said housing.

5. A bank, including a bank body having an opening therein, a closure member for said opening, means for releasably locking said closure member on said bank body, a coin slot, a housing having an open bottom surrounding said coin slot and tumblers arranged within said housing on opposite sides of said slot, the pivotal movement of 30 said tumblers in opposite directions with respect to each other being limited by the side walls of said housing.

6. A bank of the class described comprising a body, open at one side; a closure member for said open side; a partition mounted in said body in spaced relation with respect to one of the side edges thereof; oppositely disposed reciprocating lock plates mounted in said space between said side edge and 40 said partition; means for reciprocating said plates toward each other; and means mounted on said cover engaging said plates for locking said cover in closed position on said body, substantially as described.

45 7. A bank of the class described comprising a body having a slot formed in one of the end walls for the deposit of money into said body; means for closing the passage of said slot; a closure member for said body; a partition mounted in said body in spaced 50 relation with respect to one of the side edges of said body; a recess formed in said partition; a flanged disc mounted in said recess; and means operable by said flanged disc for locking and unlocking said cover on said closure member, substantially as described.

8. A bank of the class described comprising a body; a closure member on said body; a partition mounted in said body in spaced relation with respect to one of the side edges 60 of said body; a centrally formed recess in said partition; a flanged disc rotatably mounted in said recess; oppositely disposed ears formed on said disc; laterally extending pins formed adjacent the outer ends of 65 said ears; oppositely disposed reciprocating lock plates mounted in said space between said partition and said side edge; transversely extending slots formed in each of said plates for the reception of said pins; 70 means for rotating said disc for reciprocating said lock plates toward each other when unlocking said cover; and means for reciprocating each of said lock plates away from each other, substantially as described. 75

9. A bank including a coin chamber, a coin slot, a housing having an open bottom surrounding said coin slot and means pivotally mounted in said housing for controlling passage through said coin slot, the pivotal 80 movement of said means in one direction being limited by the side walls of said housing.

10. A bank including a body substantially book shaped and provided with a releasably held wall portion; a coin slot formed in one of said walls of said body and rectangularly shaped eccentrically mounted members controlling the passage through said coin slot. 85

11. A bank including a coin chamber, a coin slot formed in one of the walls of said bank, parallel members on opposite sides of said slot, and rectangularly shaped tumblers eccentrically carried by said members for controlling the passage through said slot. 90 95

12. A bank including a coin chamber, a coin slot formed in one of the walls of said bank, parallel members on opposite sides of said slot, rectangularly shaped tumblers eccentrically carried by said members and adapted to pivot by gravity toward said slot, and means for limiting the pivotal movement of said tumblers in the opposite directions. 100

In testimony whereof I have signed my name to this specification in the presence of two subscribing witnesses.
